John Dailey Inventor

UNITED STATES PATENT OFFICE.

JOHN DAILEY, OF VAN WERT, OHIO, ASSIGNOR TO WILLIAM SMITH AND WILLIAM M. SMITH, BOTH OF SAME PLACE.

DRAFT-EQUALIZER.

SPECIFICATION forming part of Letters Patent No. 364,487, dated June 7, 1887.

Application filed March 4, 1887. Serial No. 229,718. (No model.)

To all whom it may concern:

Be it known that I, JOHN DAILEY, a citizen of the United States, residing at Van Wert, in the county of Van Wert and State of Ohio, 5 have invented a new and useful Improvement in Clevises, of which the following is a specification.

My invention relates to clevises for attaching singletrees to doubletrees and for other 10 purposes, and aims to provide a device whereby the draft upon the animals may be equalized without employing any of the cumbersome forms of whiffletrees technically known as "draft-equalizers." This object I attain by 15 the use of the device shown in the accompanying drawings; and the novelty consists in certain features thereof, hereinafter fully described, and particularly pointed out in the claims.

20 In the drawings, Figure 1 is a perspective view of the end of the doubletree provided with my improved clevis. Fig. 2 is a side elevation of the clevis, and Fig. 3 is a central longitudinal section of the same.

25 Referring to the drawings by letter, A designates the doubletree, and B re-enforcing metallic strips or bands secured to the opposite sides or edges of the same. These strips or bands B are provided with a series of corrugations, C, the purpose of which will be herein- 30 after fully set forth.

The clevis consists of the coupling-link D and the stirrups E and suitable connecting and fastening devices, all of which I will now 35 proceed to describe. The coupling-link D encircles the end of the whiffletree and extends a short distance forward of the same, as shown, in order to receive the ring secured to the rear side of the singletree. The front end of the 40 coupling-link D is also made semicircular in order to more easily and perfectly engage the said ring aforesaid. The rear end of the coupling-link is formed by a cross-bar, d, the rear side of which is flat and smooth, and the front 45 side of which is provided with a longitudinal rib, d', which engages the corrugations C of the band on the rear side of the doubletree.

F designates longitudinal slots in the sides of the coupling-link, near its forward end, and

G is a socket formed in the rear side of the 50 cross-bar d, and which will be presently more fully referred to.

The stirrup E is a U-shaped metallic bar so arranged that the shoulder of the U is in rear of and abuts against the cross-bar d of the 55 coupling-link, while the arms of the U extend forward alongside the sides of the coupling-link. The ends of the stirrup E are provided with perforations e, through which and the slots F, I pass a bolt, pin, or similar device, 60 H, which engages the corrugations in the band on the front side of the doubletree. I is an adjusting and securing bolt or screw which passes through a screw-threaded opening in the shoulder of the stirrup and engages or enters the 65 socket G in the cross-bar d of the coupling-link. The end of this screw or bolt I is not screw-threaded, and consequently acts or rests in the socket G, as in a journal-box, so that when it is turned, instead of going through the 70 said cross-bar, it will push the same forward into engagement with the corrugations C, hereinbefore mentioned.

The rear lower corner of the shoulder of the 75 stirrup is bent out of the straight line of the main portion of the same to form the groove or loop J to receive and hold the coockeye K, to which is secured one end of the chain which extends from the doubletree to the axle of the vehicle.

Having thus described the construction and arrangement of the several parts of my device, its operation is as follows: The coupling-link and stirrup are placed in proper position and the securing-screw inserted through the ends 85 of the same, as described. The several parts are then placed at a point on the whiffletree where the cross-bar d and bolt H will engage the corrugations when the bolt I is operated. The said bolt I is then turned so as to cause 90 the said cross-bar and bolt to engage and bind against the corrugations, as will be understood.

It will be seen that my device can be quickly and easily applied to the doubletree, and consists of very few parts, and those few of simple 95 construction. By securing the device to the doubletree at a greater or less distance from the tongue of the vehicle the leverage will be

increased or diminished, and in this way the draft upon the animals may be equalized according to their strength.

Having thus fully described my invention, 5 what I claim as new, and desire to secure by Letters Patent of the United States, is—

1. The combination, with the doubletree, of the coupling-link encircling the same, the stirrup embracing the coupling-link, and mechanism whereby the stirrup and coupling-link are made to mutually bind against the opposite sides or edges of the doubletree, as set forth.

2. The combination, with a doubletree having a series of corrugations on its opposite 15 sides, near its end, of the clevis having means for engaging the corrugations and binding within the same, substantially as set forth.

3. The combination, with the doubletree, of the coupling-link having one end bearing 20 against the whiffietree and having slots in its

sides, near its opposite ends, the stirrup embracing the coupling-link and carrying a bolt, pin, or similar device which passes through the slots in the sides of the coupling-link, and a screw or bolt passed through the shoulder 25 of the stirrup and journaled in the end of the coupling-link, substantially as specified.

4. The combination, with the doubletree, of the coupling-link adjustably secured thereto, and the stirrup connected with the coupling-link and carrying the cockeye, as and for the 30 purposes specified.

In testimony that I claim the foregoing as my own I have hereto affixed my signature in presence of two witnesses.

JOHN DAILEY.
